United States Patent Office

Des. 224,222

Patented July 11, 1972

224,222

WASH BASIN

Delmas E. Collins, West Lafayette, Ohio, assignor to
Jones-Zylon, Inc., West Lafayette, Ohio

Filed Oct. 30, 1970, Ser. No. 25,753

Term of patent 14 years

Int. Cl. D23—02

U.S. Cl. D23—48

Fig. 1

Fig. 2

Fig. 3

Fig. 4Fig. 5Fig. 6Fig. 7

FIG. 1 is a perspective view of a wash basin showing my new design;

FIG. 2 is a top plan view thereof;

FIG. 3 is a bottom plan view thereof;

FIG. 4 is a front elevation thereof;

FIG. 5 is a rear elevation thereof;

FIG. 6 is an elevation taken from the right side thereof; and

FIG. 7 is an elevation taken from the left side thereof.

I claim:

The ornamental design for a wash basin, as shown.
